UNITED STATES PATENT OFFICE.

EMIL J. CARROLL, OF CINCINNATI, OHIO, ASSIGNOR TO THE AMERICAN LAUNDRY MACHINERY COMPANY, OF CINCINNATI, OHIO, A CORPORATION OF OHIO.

OVERDRIVEN EXTRACTOR.

Application filed July 2, 1921. Serial No. 482,176.

This invention relates to centrifugal extractors such as are used for extracting the moisture, water or cleaning fluids from fabrics or clothing during treatment thereof in 5 laundries, dry cleaning plants, textile mills or the like.

The object of the invention is to provide an improved extractor, and more particularly an extractor of the over driven type, in 10 which the rotating spindle and basket are electrically driven by a motor, the armature or rotor of which is fast with the spindle and the field frame of which is mounted upon a part which is relatively stationary 15 as regards the spindle, the arrangement being such as to simplify the bearing construction and safeguard the motor from the bad effects of shock, jar and vibration due to unbalanced loads.

20 Further objects of the invention are in part obvious and in part will appear more in detail hereinafter.

In the drawings Fig. 1 represents a front elevation of an extractor embodying the invention; and Fig. 2 is a detail section on a larger scale, on the line 2—2, Fig. 1.

The extractor shown in the drawings comprises a relatively stationary frame including a base 1 resting upon the floor or other 30 support and upwardly extending members 2 connected at their upper ends to form a support for the basket and curb, as will appear. 3 represents the curb which is a hollow bowl shaped member provided with upwardly extending arched supporting members 4 formed to provide a vertical guide and bearing 5 for the spindle 6 which supports the basket 7 having the usual perforated outer wall 8. In the bottom of the curb are 40 located suitable bearing devices 9 for supporting and guiding the spindle 6.

The spindle 6 may also be guided and supported in an intermediate bearing 11 carried by a cross-bridge 12 extending horizontally across between the upright members 4 carried by the curb.

With this arrangement the spindle and basket rotate in the curb member and the basket and curb swing or oscillate together 50 or as a unit about a point near the top of the frame, so as to enable the basket and curb by such motion to compensate for unbalanced loads and thereby produce a true spinning motion without shock or vibration.

The movable curb member is therefore suspended from the stationary frame member in any suitable manner to provide free swinging motion horizontally in all directions, such as by a universal joint. In the arrangement shown the curb member is hung 55 and swings from front to rear upon a pivot pin 13 which in turn is carried by a member 14 pivoted to swing from right to left upon the pin 15 carried by the stationary frame.

The basket and spindle are rotated by an 60 electric motor which may be of any suitable form. The drawings represent said motor somewhat diagrammatically. It comprises a rotor or armature 16 attached to the basket spindle 6 and turning within the 65 stator or field frame 17 which is supported by the cross-bridge 12 and is therefore stationary relative to the swinging curb member.

By supplying current to the motor the entire power effect is converted into pure torque upon the basket spindle and with absolutely no lateral pull such as would be exerted by the effect of a driving belt upon a pulley carried by the spindle. The normal tendency of the basket spindle is therefore to merely spin about the motor axis. In case the load in the basket is out of true balance the basket and curb members swing together or as a unit to one side or the other 75 to compensate for the unbalanced condition. This motion, however, carries both parts of the motor, to wit, the rotor and field frame, with the swinging parts. As a result, the usual shock, jar and vibration of unbalanced 80 loads are not communicated to the motor parts nor are they transmitted through such parts to the frame. Also, the bearings for the basket spindle need not be long and heavy as is the usual construction in this 85 type of extractor, but can be relatively short and simple, merely serving to support and guide the spindle in its proper axial position with the necessary clearance in the motor parts. As a result, the cavity within 90 the basket is largely increased by doing away with the upwardly extending central conical portion which usually covers the long bottom bearing of the basket spindle in the curb. The motor clearance is also maintained uniform. The use of an electric motor directly connected to the spindle also enables 95

100 electric braking effects to be employed, there- 105

by doing away with the lateral or horizontal pushing effect of a brake shoe upon a pulley or drum carried by the spindle. That is to say, in the present arrangement the motor, if it is a D. C. motor, will be braked by a dynamic braking effect and if an A. C. motor by reverse phase braking. Therefore, neither the driving nor the braking effects produce lateral or horizontal strains upon the spindle.

10 What I claim is:

An extractor, comprising curb and basket members arranged to swing together about a

joint from which they are suspended, a basket spindle having three separated bearings, upper, lower, and intermediate, in the curb member, the basket being secured to the spindle between the lower and intermediate bearings, and an electric motor having a rotatable part directly connected to 15 said spindle between the upper and intermediate bearings for driving the spindle.

20 In testimony whereof I hereby affix my signature,

EMIL J. CARROLL.
